[57] CLAIM

The ornamental design for a wheel for motor vehicle, substantially as shown and described.

DESCRIPTION

FIG. 1 is a perspective view from the front and to one side of a wheel for a motor vehicle showing a first embodiment of my new design;

FIG. 2 is a front elevational view thereof;

FIG. 3 is a rear elevational view thereof;

FIG. 4 is a side elevational view thereof;

FIG. 5 is a perspective view from the front and to one side of a wheel for a motor vehicle showing a second embodiment of my new design;

FIG. 6 is a front elevational view of the wheel shown in FIG. 5 it being understood that the rear is a mirror image thereof; and

FIG. 7 is a side elevational view of the wheel shown in FIG. 5.
